UNITED STATES PATENT OFFICE.

WILLIAM H. ODLUM, OF CHICAGO, ILLINOIS, ASSIGNOR TO DURO METAL PRODUCTS COMPANY, OF CHICAGO, ILLINOIS, A CORPORATION OF ILLINOIS.

DESIGN FOR AN ELECTRICAL VAPORIZING DEVICE.

Application filed May 16, 1928. Serial No. 26,697. Term of patent 14 years.

To all whom it may concern:

Be it known that I, WILLIAM H. ODLUM, a citizen of the United States, residing at Chicago, in the county of Cook and State of Illinois, have invented a new, original, and ornamental Design for an Electrical Vaporizing Device, of which the following is a specification, reference being had to the accompanying drawing, forming part thereof.

Figure 1 is a top plan view of an electrical

vaporizing device showing my new design.

Figure 2 is a side elevational view of the same.

I claim:

The ornamental design for an electrical vaporizing device, as shown.

In witness whereof, I hereunto subscribe my name, this 18th day of April, 1928.

WILLIAM H. ODLUM.
